(57) **CLAIM**

The ornamental design for a fish skinning hook, as shown and described.

DESCRIPTION

FIG. 1 is a first oblique side perspective of a fish skinning hook;

FIG. 2 is a second oblique side perspective of the fish skinning hook;

FIG. 3 is a front perspective view of the fish skinning hook;

FIG. 4 is a rear perspective view of the fish skinning hook;

FIG. 5 is a top view of the fish skinning hook;

FIG. 6 is a top view of the fish skinning hook with a fastener for mounting;

FIG. 7 is a first side view of the fish skinning hook;

FIG. 8 is an opposing side view of the fish skinning hook; and,

FIG. 9 is a top view of the fish skinning hook being mounted for use thereof.

The broken lines in the drawings depict portions of the fish skinning hook that form no part of the claimed design.
